UNITED STATES PATENT OFFICE

CARL LUTE, OF CHICAGO, ILLINOIS, ASSIGNOR TO CAMEL COMPANY, OF CHICAGO,
ILLINOIS, A CORPORATION OF ILLINOIS

CAR DOOR ELEVATING MEANS

Application filed February 1, 1930. Serial No. 425,128.

This invention relates to a ball bearing mounting for a sliding door primarily designed for house cars and concerns itself with a novel structure whereby the door may be supported in frictional engagement upon its track against sliding movement or may be supported upon the ball bearings for rolling movement.

The invention comprises the novel structure and combination of parts hereinafter described, and more particularly pointed and defined in the appended claims.

In the accompanying drawings which illustrate a preferred form of this invention and in which similar reference numerals refer to similar features in the different views:

Figure 1 is a fragmentary side elevational view of a door for a house car mounted according to this invention.

Figure 2 is an enlarged fragmentary sectional view taken on the line II-II of Figure 3.

Figure 3 is an enlarged fragmentary elevational view of the lower central part of the door.

Figure 4 is an enlarged sectional view taken upon the line IV-IV of Figure 5 illustrating the door in its elevated position and supported by the roller mounting.

Figure 5 is an enlarged fragmentary plan view similar to Figure 3 illustrating the door in its elevated position.

Figure 6 is an elevational view of a cam member positioned between the door and the roller mounting for elevating the door when it is desired to support the same upon the roller mounting.

In referring to the drawings, it will be noted that the track 1 is supported adjacent the lower margin of the door opening. A door 2 of any usual construction is adapted to be supported upon this track by either frictional pads 3 (Figure 1) adjacent the ends of the door or upon a roller mounting 45 which is connected to the door for relative longitudinal and vertical movement. The roller mounting consists of a longitudinally extending V-shaped raceway 4 which has a depending wing 5 which extends contiguous to the outer surface of the door as shown

more clearly in Figures 2 and 4. The depending wing of the raceway 4 is provided with a plurality of rectangular apertures 6. A substantially triangular cam member 7 is located in each aperture 6 and is pivoted to the door upon a stud 8. In referring to Figures 5 and 6, it will be noted that each cam member 7 has a pair of lobes at its base which normally rest in slight depressions formed in the bottom of the apertures 6.

A plurality of bearing balls 9 are located in the raceway 4 for relative longitudinal movement thereof and for travelling engagement upon the track 1 and supporting the door thereon when the same is elevated so that the friction pads 3 no longer engage the track.

These rolling elements 9 may be retained in suitable retainers or spacers, and to this end there is shown a retainer and spacing element 10 which consists of a wire rod having upwardly offset spherical recesses 12 for receiving the bearing balls 9. A Z-bar 13 is attached to the lower portion of the door and extends longitudinally thereon above the ball raceway 4. A yoke 14 is rigidly secured to the raceway 4 and extends through a slot in the web of the Z-bar 13. The upper portion of the yoke 14 is provided with a laterally offset bearing boss 15 upon which a lever 16 is journaled intermediate its edges. The depending flange of the Z-bar 13 is also cut away adjacent the lever 16 and a plate 17 which is attached to the Z-bar 13 spans this cut away portion. This plate 17 is provided with a vertical slot 18 for receiving a lug 19 upon the lower end of the lever 16 whereby a lost motion connection is provided between the lever and the Z-bar 13 which constitutes a rigid part of the door. This lost motion connection allows the lever 16 to shift the raceway 4 relative to the door. During such shifting movement of the raceway 4, it is desirable to maintain the depending wing 5 in proper position and for this purpose a suitable plate 20 is attached to the door in suitable spaced relation to receive the wing 5 and the cam 7 therebetween. It will be noted that a plurality of such plates 20 are used, one at each aperture 6 in the depending wing.

Normally the door is supported upon the 100

track 1 by means of the friction pads 3 against any sliding movement due to the sudden starting or backing of the car. When it is desired to elevate the door in order that it may be supported upon the roller mounting for sliding or rolling movement, the operator will grasp the handle 16 and pull the same in one direction. Assume that it has been pulled toward the left as shown in Figure 5, the raceway 4 will be moved to the left due to the fact that the lower end of the lever is anchored in the slot 18. As the raceway 4 is thuswise longitudinally shifted relative to the door, the cam members 7 will rock as shown in Figure 5 for the purpose of elevating the door so that it is no longer supported upon the friction pads 3 but will, on the other hand, be supported by the roller mounting so that the same can be slid or rolled upon its track to either its opened or closed position. As soon as the lever 16 is released, the door will descend by its own weight until it is again supported upon its friction pads.

I am aware that numerous details of construction may be varied through a wide range without departing from the principles of this invention, and I therefore do not purpose limiting the patent granted, otherwise than necessitated by the prior art.

30 I claim as my invention:

1. The combination with a track, of a door having means for frictionally engaging said track, a V-shaped ball runway carried by said door for relative longitudinal movement with respect thereto, and means between said door and runway responsive to said longitudinal movement for elevating said door and rolling means in said runway for supporting said door upon said track in its elevated position.

2. The combination with a track, of a door having means for frictionally engaging said track in its lowered position, a ball retainer carried by said door, balls in said retainer for travelling movement upon said track, said retainer and door being mounted for relative longitudinal movement, and means between said door and retainer responsive to such longitudinal movement for elevating said door for the purpose set forth.

3. The combination with a track, of a door mounted for movement toward and from said track, means upon said door for frictionally supporting the same in its lowered position upon said track, a ball runway carried by said door, balls in said runway for travelling movement upon said track when said door is in its elevated position, said door and runway being connected for relative longitudinal movement and means between said door and runway responsive to such relative longitudinal movement for elevating said door.

4. The combination with a track, of a door mounted for movement toward and from said track, frictional means carried by said door

for engaging said track in its lowered position, a ball raceway carried by said door, balls in said raceway for travelling movement upon said track, said raceway having a depending wing connected to said door for relative longitudinal movement, said wing having cut out portions, cams mounted in said cut out portions and pivoted to said door for the purpose set forth.

5. The combination with a track, of a door having means for frictionally engaging said track, a ball raceway carried by said door, balls mounted in said raceway, said raceway having a depending portion positioned adjacent said door, said depending portion having cut out portions, cam members mounted in said cut out portions and pivoted to said door, a lever pivoted to said door and having a connection with said raceway for causing relative movement between said door and raceway whereby said cams may elevate the door relative to said track.

6. The combination with a track, of a door having pads for engaging said track, a roller raceway mounted upon said door for relative longitudinal movement, balls mounted in said raceway for travelling movement upon said track, and a lever having a connection with said door and race way for the purpose set forth.

7. The combination with a track, of a door having friction pads for engaging said track, a ball raceway carried by said door for relative movement with respect thereto, and movable members between said door and raceway for elevating said door through such relative movement of said door and raceway.

8. The combination with a track, of a door mounted upon said track for raising and lowering movement, friction pads upon said door for engaging said track when said door is lowered, anti-friction means carried by said door for supporting the same upon said track when said door is elevated, a raceway for said anti-friction means, and means for causing relative longitudinal movement between said raceway and door, and cams between said door and raceway for causing relative vertical movement between said door and raceway.

9. The combination with a track, of a door having frictional pads for engaging said track, a ball raceway having a depending flange with apertures, cam members mounted in said apertures and pivoted to said door, balls supported in said raceway for travelling movement upon said track, a support upon said door, a lever having a lost motion connection with said support, means for connecting said lever and raceway whereby the latter may be shifted relative to the door for actuating said cams for elevating the door for the purpose set forth.

10. The combination with a track, of a door, a ball bearing mounting between said

door and track, means for causing relative longitudinal movement between said ball bearing mounting and door, and means set in motion by said relative longitudinal movement for elevating said door for supporting the same upon said ball bearing mounting and track.

11. The combination with a track, of a door, a ball bearing mounting between said door and track, means for connecting said ball bearing mounting and door for limited relative longitudinal movement, said means serving to elevate the door during said relative longitudinal movement.

12. The combination with a track, of a door having frictional means for engaging said track, a ball raceway carried by said door, balls mounted in said raceway for relative longitudinal movement thereof, said raceway having a depending wing with apertures, elevating members in said apertures and pivoted to said door, a support upon said door, a lever pivoted upon said support and means connecting said lever and raceway.

13. The combination with a track, of a door having frictional means for normally engaging said track, a ball retainer extending along the lower margin of the door, spaced balls mounted in said raceway for relative longitudinal movement thereof, said retainer having portions extending adjacent said door, said portions having apertures, door elevating members pivoted to said door and located in said apertures and means for causing relative longitudinal movement between said door and raceway for causing said members to elevate the door.

14. The combination with a track, of a door having frictional means normally engaging said track, a ball raceway carried by said door, spaced balls mounted in said raceway for relative longitudinal movement, means for causing relative longitudinal movement of said door and raceway and elevating members between said door and raceway for elevating the door during such relative longitudinal movement.

15. The combination with a track, of a door having frictional pads for normally engaging said track, a roller raceway mounted upon said door for relative longitudinal movement thereof, and for travelling movements upon said track, means for causing relative longitudinal movement between said door and track and means between said door and raceway responsive to such last mentioned movement for elevating said door.

In testimony whereof I have hereunto subscribed my name at Chicago, Cook county, Illinois.

CARL LUTE.
